PEDESTAL BASE FOR STATUETTES

Alexander Pistey, 165 Alpine St., Bridgeport, Conn.

Filed Feb. 1, 1961, Ser. No. 63,794

Term of patent 14 years

(Cl. D29—23)

FIG. 1 is a front elevational view of a pedestal base for statuettes, showing my new design;

FIG. 2 is a top plan view thereof;

FIG. 3 is a transverse sectional view, taken on the line 3—3 of FIG. 1; and

FIG. 4 is a longitudinal sectional view, taken on the line 4—4 of FIG. 3.

I claim the ornamental design for a pedestal base for statuettes, substantially as shown.
